UNITED STATES PATENT OFFICE.

FRED LACEY, OF LOWELL, MASSACHUSETTS, ASSIGNOR TO DRAPER CORPORATION, OF HOPEDALE, MASSACHUSETTS. A CORPORATION OF MAINE.

FEELER MECHANISM FOR LOOMS.

1,362,118.

Specification of Letters Patent. Patented Dec. 14, 1920.

Application filed January 20, 1920. Serial No. 352,724.

To all whom it may concern:

Be it known that I, FRED LACEY, a citizen of the United States, and a resident of Lowell, in the county of Middlesex and State 5 of Massachusetts, have invented an Improvement in Feeler Mechanisms for Looms, of which the following description, in connection with the accompanying drawings, is a specification, like characters on the drawings 10 representing like parts.

This invention relates to feeler mechanisms for looms, whereby, when the filling in the shuttle becomes substantially exhausted, but prior to complete exhaustion, a train of 15 mechanism is set in operation for effecting replenishment of filling.

Automatic looms of this type are now commonly known as "feeler looms" because ordinarily equipped with a movable device or 20 feeler which periodically enters the shuttle and feels for the filling therein. In the practical use of such mechanisms there are various disturbing factors which detract from the sensitiveness of the feeler and consequently its desired accuracy of operation. While these various factors are minute they 25 are of importance, because should the feeler mechanism call for a change of filling prior to substantial exhaustion thereof in the 30 working shuttle, an unnecessary waste of filling occurs, and should it fail to call for a change or replenishment of filling when the filling in the active shuttle reaches a degree of substantial exhaustion, a mis-pick 35 or only a partial pick may be laid in the shed with the result that imperfect cloth will be woven.

The main object of the present invention is to provide feeler mechanism which will 40 be free from the usual disturbing causes which tends to impair feeler mechanisms and which can, accordingly, be rendered sensitive either to the presence or substantial absence of filling.

An important feature of the present invention, therefore, consists of a feeler carrier having a feeler pivotally mounted thereon to be movable therewith and relatively thereto by the forward push against it and 45 which is held from movement longitudinally of the shuttle on a detecting beat by engagement with the filling until substantial exhaustion thereof, and a second lever also pivotally mounted on the feeler carrier to

be engaged by the shuttle and actuate a train 55 of mechanism to effect replenishment of filling, when the feeler member is moved longitudinally of the shuttle by the forward push on a detecting beat.

In the drawing:

Figure 1 is a plan view representing the detecting side of the loom with the present invention associated therewith;

Fig. 2 is an enlarged plan view showing the action of the feeler mechanism when a 65 working supply of filling is present in the shuttle on a detecting beat;

Fig. 3 is a view similar to that of Fig. 2 showing the action of the feeler mechanism when the filling is substantially exhausted. 70

The loom frame 1 has mounted thereon the transverse or rock shaft 2 from which rises the arm 3 to which is pivotally connected the latch 4, the rear end portion of which is adapted at times to be engaged by 75 an operating member 5 which may be connected to the cam follower or weft hammer. These features are usual in feeler looms of this type and need no further description as they are well understood by those familiar 80 with the art.

The lay 6 may be of usual construction and provided with a shuttle box 7 for the reception of the shuttle 8 carrying the bobbin 9 on which is wound the filling 10, as 85 usual. The front wall 11 of the shuttle box is provided with a slot 12 and likewise the adjacent wall of the shuttle 8 is provided with a slot 13 which registers with the slot 12 when the shuttle is properly boxed at the 90 detecting side of the loom, the construction being such that the feeler, to be hereinafter described, may enter the shuttle on each detecting beat and ascertain the condition of the filling therein. 95

The loom frame or shipper stand has mounted thereon the feeler carrier, of which there are several types in the art. In the present instance the feeler carrier 14 is mounted for sliding movement toward and 100 from the front of the loom in a feeler stand 15 supported by the shipper stand 16. The feeler carrier 14 has a forwardly extending stem portion 17 by which the feeler carrier is guided in its movement toward and 105 from the front of the loom, and a spring 18 normally maintains the feeler carrier in its rearward feeling position. The parts so far

described are or may be substantially the same as the similar parts more fully shown and described in the patent to Wood and Northrop No. 789,471, dated May 9, 1905, wherein is shown what is commonly known in the art as the "Draper" feeler. The feeler carrier 14 is provided with an extension 19 which preferably projects outwardly at one side of the feeler carrier, as indicated in the drawings, and to the extension the feeler 20 is pivotally connected at 21. The feeler 20 is constituted as a lever horizontally pivoted upon the feeler carrier and its rearwardly extending end portion is offset to one side of the pivotal support 21 connecting the feeler and feeler carrier, and is provided with teeth or a roughened surface 22 for engagement with the filling or a surface within the shuttle on each detecting beat.

Extending from the feeler 20 is a fan-tail 23 which is provided with a series of openings 24 into any one of which one end of a spring 25 may be engaged, said spring acting through the fan-tail to normally hold the feeler 20 in its feeling position, as fully carried in Fig. 1, but with permissive movement about its pivotal support in either direction. In the present instance of the invention, the spring 25 has its front end portion 26 adjustably connected by an arm 27 and screw 27' to the stem 17 of the feeler carrier, the construction being such that as the feeler carrier moves forwardly under the impact of the surface within the shuttle against the feeler on its detecting beat, the spring 25 will act continuously upon the feeler without disturbance.

The feeler carrier 14 is provided with a second lever 28 which is pivotally mounted on an axis 29 to move in a vertical plane or at right angles to the pivotal movement of the feeler 20. The second lever 28 may be conveniently designated for identification as the controller actuator and may be substantially the same as the corresponding part in the patent hereinbefore mentioned. The controller actuator extends forwardly from its pivotal support 29 and its front end portion 30 is normally held raised for movement in a path forwardly of the loom above the controller 31 by means of a spring actuated pin 32, substantially as more fully described in the patent hereinbefore mentioned.

The controller 31 is pivotally mounted at 33, Fig. 1, to swing toward and from the front of the loom and between its pivotal point and free end it passes over a part 34 of the transmitter 35 which, as indicated in the patent heretofore referred to, may be pivotally supported at 36 upon a lug 37 rising from the loom frame or shipper stand, the construction being such, as more fully disclosed in the patent, that when the controller 31 is moved forwardly by the con-

troller actuator 28, it will turn the transmitter 35 about its pivotal support 36 and cause its end portion 38 to place the latch 4 in the path of movement of the operating member 5 and, perforce, effect replenishment 70 of filling.

The controller actuator or second lever 28 has a bunter 38 to the rearward of which extends the end portion 22 of the feeler, the construction being such that when a working 75 supply of filling is present in the shuttle, the feeler will engage the filling and together with the feeler carrier and controller actuator or second lever, will be moved forwardly by the forward pressure against 80 the feeler, the bunter 38 at such times assuming substantially the relative position with respect to a part on the lay, such as the shuttle, as indicated in Fig. 2.

In operation when a working supply of 85 filling is present in the shuttle on a detecting beat, the toothed end portion 22 of the feeler will engage the filling and the feeler will be prevented from movement in a direction longitudinally of the shuttle by the 90 filling as the lay moves forwardly, the action of the parts at such times being indicated in Fig. 2, and the bunter 38 will not be engaged by its cooperating part carried by the lay. When, however, the filling is 95 substantially exhausted on a detecting beat, the toothed end portion 22 of the feeler 20 will again engage a surface within the shuttle such, for instance, as the filling carrier or bobbin 9, and will be caused to slip or 100 slide along the filling carrier or bobbin by the forward pressure as the lay moves forwardly. The result of this is that the bunter 38 on the second lever or controller actuator will now be permitted to engage 105 the part, such as the shuttle, on the lay, and through the pressure against the bunter, the end 30 of the second lever or controller actuator will be depressed into position to engage the controller 31 as the actuator, feeler, 110 and feeler carrier move forwardly under the forward pressure against the bunter. The forward movement of the controller 31 will be transmitted through the transmitter to the latch 4 and, as hereinbefore indicated, filling replenishment will be called.

Claims:

1. In a feeler mechanism for looms, the combination of a feeler carrier mounted for movement toward and from the front of the 120 loom, an actuator supported by the carrier in position to engage a part carried on the lay and arranged to be operated by said engagement to effect replenishment of filling, a feeler pivoted between its ends to the feeler carrier and having oppositely directed arms one of which is offset from the pivot and is positioned to engage the filling upon a detecting beat, and a feeler positioning spring connected to the other arm and arranged to 130

exert a frontward pull upon the same in a direction passing through the pivotal axis of the feeler.

2. In a feeler mechanism for looms, the combination of a feeler carrier mounted for movement toward and from the front of the loom, an actuator for effecting replenishment of filling pivotally mounted on the feeler carrier to engage the shuttle when filling is to be changed, a feeler pivoted to the feeler carrier for movement longitudinally of the shuttle in either direction from normal feeling position, said feeler having arms one of which is offset from the pivot and is positioned to engage the filling on a detecting beat, the other arm of the feeler being provided with a plurality of apertures, and a feeler positioning spring constructed to be connected with any one of said apertures and exert a frontward pull to retain the feeler in different feeling positions.

10 5 15 20

3. In a feeler mechanism for looms, the combination of a feeler carrier mounted for movement toward and from the front of the loom, an actuator for effecting replenishment of filling pivotally mounted on the feeler carrier to engage the shuttle when filling is to be changed, a feeler pivoted to the feeler carrier for movement longitudinally

of the shuttle in either direction from normal feeling position, said feeler having arms one of which is offset from the pivot and is positioned to engage the filling on a detecting beat, the other arm of the feeler being provided with a plurality of apertures, and a feeler positioning spring constructed to be connected with any one of said apertures and exert a frontward pull to retain the feeler in different feeling positions.

4. In a feeler mechanism for looms, the combination of a feeler carrier mounted for movement toward and from the front of the loom, an actuator pivotally mounted upon the carrier in position to engage a part carried by the lay when filling is to be changed, a feeler mounted upon the feeler carrier for movement laterally in either direction from normal feeling position, a feeler positioning spring which exerts its energy through the mounting of the feeler, and adjustable connections between the spring and feeler for determining the relative normal positions of the feeler and actuator.

10 15 20 25 30 35 40 45 50

In testimony whereof I have signed my name to this specification.

FRED LACEY.
